UNITED STATES PATENT OFFICE

JOHN A. ANDERSON, OF BRIDGEPORT, CONNECTICUT, ASSIGNOR TO THE BRIDGEPORT HARDWARE MANUFACTURING CORPORATION, OF BRIDGEPORT, CONNECTICUT, A CORPORATION OF CONNECTICUT

SCREW DRIVER

Application filed December 24, 1929, Serial No. 416,227, and in Great Britain November 29, 1929.

This invention relates to screw drivers, and has for an object to improve upon the present-day construction of screw drivers by providing them with means to prevent their slipping in the screw head kerf during their turning movements and thus, not only prevent injury to the work being done or to the operator, but also to permit faster operation and thus increase production.

It is also an object of the invention to provide a construction which can be used to effectively operate screws in which the kerf has been so deformed as to be incapable of operation by the ordinary plain screw driver.

With the foregoing and other objects in view, the invention consists in certain novel features of construction and arrangement of parts as will be more fully disclosed in connection with the accompanying drawing.

In this drawing

Fig. 1 is a side elevation of a screw driver shank constructed according to the preferred embodiment of the invention.

Fig. 2 is a fragmentary edge elevation of the same on an enlarged scale showing the screw driver in the kerf of a screw.

Fig. 3 is an enlarged section substantially on line 3—3 of Fig. 1.

Fig. 4 is an enlarged end view taken substantially as indicated by line 4—4 of Fig. 1, and

Fig. 5 is an enlarged fragmentary longitudinal section substantially on line 5—5 of Fig. 1.

The shank 10 of the screw driver, as is usual, is provided with two opposite side faces 11 and 12 and two edge faces 13 and 14. On either one or both of the side faces 11 and 12 there is provided a transverse rib 15 which extends transversely of the bit closely adjacent the free end 16 of the bit.

The free edge of this rib is sufficiently sharp to bite into the side walls of the kerf 17 of the screw head 18 upon turning movement of the screw driver in the kerf, and the biting action very effectively resists slipping of the bit from the kerf in a direction longitudinally of the shank. The side face or faces of the bit are also provided with means above the rib 15 to bite into the

wall of the kerf during the turning movement of the bit to prevent slipping of the bit transversely in the kerf or to resist both transverse and longitudinal slipping. Various means may be provided for doing this, but I have shown in the accompanying drawing two series of inclined ribs 19 and 20, these ribs being preferably arranged to extend obliquely from the longitudinal center line 21 to the opposite edge faces 13 and 14 and inclined toward the free end 16. The angle of inclination may vary depending on whether it is desired to emphasize resistance to lateral slipping in the kerf or resistance to longitudinal slipping.

With the ribs inclined as shown, their action on turning movement of the bit tends to draw the bit into the kerf as well as to resist its slipping from the kerf and thus more effectively assists in holding it in the kerf. This construction and arrangement using the transverse rib 15 in combination with the other holding means is quite an improvement over a construction in which the ribs 19 and 20 only are provided and run out the end 16. Particularly is this true in a case where the bit is used in a kerf which is relatively shallow or has been badly worn or deformed.

In such cases, the transverse rib 15 materially assists in gripping the kerf for operating a screw. Also the ribs 15 strengthen the free end of the bit which is the thinnest portion of the bit and is also the portion which is more apt to be broken or injured. The ribs 15 make this end portion much stronger.

The ribs and holding means may be formed in any manner desired as for example, raising them on the surface or by providing grooves or depressions in the surface. It is also not necessary that the edges of the ribs be particularly sharp as all that is necessary is that they be sufficiently sharp to bite into the side walls of the kerf sufficiently to hold the bit against slipping. It is also not necessary that the auxiliary holding means above the transverse ribs 15 be as shown on the drawing as other shapes and arrangements of sharp edged means may be provided to bite into the side walls of the kerf in the turning operation.

In use the bit is inserted in the kerf in the same way as is any screw driver, and this screw driver does not require a special form of screw or kerf, but can be used with any 5 standard or other screw having a kerf. As a matter of fact, it will grip into a kerf which has been greatly worn or deformed to such an extent as to be practically impossible of use for operation of the screw by the ordinary 10 plain screw driver. The transverse rib 15 is particularly useful in certain kinds of kerf as it very effectively bites into the side walls thereof closely adjacent the very bottom of the kerf. The width of the kerf is practically 15 immaterial as this device is effective in both relatively wide and narrow kerfs.

Having thus set forth the nature of my invention, what I claim is:

1. A screw driver comprising a shank provided with a screw driving bit having two opposite side faces, one of said faces being provided with a rib extending transversely of said face closely adjacent the free end of the bit and extending laterally outward, said 25 face also having ribs extending from a central longitudinal line of the shank at an oblique angle to the shank toward said first rib, said oblique ribs and the transverse rib blending into each other so that they form continuations of each other and are adapted 30 to engage a wall of a screw head kerf to resist both longitudinal and transverse slipping of the bit in the kerf during the turning movement of the screw driver.

2. A screw driver comprising a shank provided with a screw driving bit having two opposite side faces and two edge faces joining the side faces, each of the side faces having a rib extending transversely of said face closely adjacent the free end of the bit, each 40 of the side faces also having ribs extending from a central longitudinal line of the shank and at an oblique angle to the shank toward said edge faces, the oblique ribs nearer the 45 end of the bit and the transverse ribs blending into each other to form continuous ribs adapted to engage opposite walls of a screw head kerf to resist both longitudinal and transverse slipping of the bit in the kerf during the turning movement of the screw driver.

In testimony whereof I affix my signature.
JOHN A. ANDERSON.
